EMORY LEE BLEVINS, OF PATTONHILL, MONTANA.

AIR-COMPRESSOR.

1,393,742.

Specification of Letters Patent. Patented Oct. 18, 1921.

Application filed August 3, 1920. Serial No. 400,932.

To all whom it may concern:

Be it known that I, EMORY LEE BLEVINS, a citizen of the United States, residing at Pattonhill, in the county of McCone and 5 State of Montana, have invented new and useful Improvements in Air-Compressors, of which the following is a specification.

This invention relates to pumping devices, particularly to air compressors, and has 10 for its object the provision of an air compressor including a cylindrical body or shell within which reciprocate, at different speeds, separate plungers arranged in parallel relation and carrying pistons, the movement of one set of pistons with respect 15 to the other compressing the air between them and forcing it out through the discharge ports in the end portions of the shell.

An important object is the provision of a 20 device of this character which is provided with gear driven means for driving the different pistons, the pistons being formed with rack teeth engaging the gears.

Another object is the provision of a device 25 of this character which will be comparatively simple and inexpensive in manufacture, highly efficient in use, positive in action, durable in service, and a general improvement in the art.

With the above and other objects and advantages in view, the invention consists in the details of construction to be hereinafter more fully described and claimed, and illustrated in the accompanying drawings in 30

35 which—

Figure 1 is a side elevation of the device, Fig. 2 is a longitudinal sectional view taken in a vertical plane,

Fig. 3 is a horizontal longitudinal sectional view,

Fig. 4 is a cross sectional view on the line 4—4 of Fig. 2,

Fig. 5 is a cross sectional view on the line 5—5 of Fig. 2, and

45 The remaining five figures are detail views.

Referring more particularly to the drawings, the numeral 10 designates a cylindrical shell which is formed of a plurality of sections 11 which are similar and which are bolted together, being provided with the usual flanges for the purpose. At their outer ends the shell sections 11 are closed by heads 12 and these heads are provided 50 with outlet ports 13 surrounded by nipples 14 which are connected by an outlet mani-

fold 15 having a discharge pipe 16 leading therefrom. Intermediate its ends, the shell 10 is formed with an inlet opening 17.

Disposed longitudinally of the shell and 60 slideable through one head 12, is a piston rod 18 which carries pistons 19 to be reciprocated within the shell. The end of the piston rod projecting from the shell may be connected with any suitable mechanism 65 whereby to effect reciprocation thereof. It will be observed that the pistons 19 are designed to coöperate with the heads 12 for compressing air into spaces between these pistons and the heads. Each piston 19 is 70 provided with a port 20 having a valve seat 21 normally closed by a spring-pressed valve 22 which is capable of opening outwardly, that is toward the heads 12.

Also disposed within the shell is a relatively short piston rod 23 carrying pistons 24 which are formed with holes 25 for the passage of the piston rod 18 and these pistons 24 are designed to coöperate with the pistons 19 for compressing air between the 80 pistons 24 and 19. The pistons 24 are formed with ports or passages 26 having valve seats 27 normally closed by spring-pressed valves 28 which open outwardly, that is toward the pistons 19. It should be 85 stated in passing that all the pistons 19 and 24 are provided with the usual or any proper packing rings such as are commonly employed for such purposes.

The piston rods 18 and 23 have formed 90 thereon racks 29 and 30, respectively, and these racks mesh with pinions 31 and 32, respectively, secured upon the shaft 33 journaled transversely of the shell at its central portion. Disposed within the upper portion of the shell immediately above the piston rods 18 and 23, is a partial partition 34 adapted to be engaged by the piston rods in the event of buckling of the latter 95 whereby to maintain the piston rods always 100 with the racks thereon meshing with the associated pinions. Owing to the fact that the pinions 31 and 32 are of different diameters, it will be obvious that the piston rod 23 and the pistons 24 carried thereby, will 105 move at a different speed from the piston rod 18 and the pistons 19 thereon, this difference in speed being necessitated by the fact that the pistons have different strokes.

In the operation of the device, power is applied to the piston rod 18 to reciprocate the pistons 19. Owing to the engagement of the

rack 29 on the piston rod 18 with the pinion 31, the shaft 33 and consequently the pinion 32 will also be rotated and this rotary movement of this latter mentioned pinion will 5 cause reciprocation of the piston rod 23 and pistons 24. It will therefore be seen that all the pistons will reciprocate within the shell but that there will be relative-movement between the pistons 19 and 24. As either piston 10 ton 24 moves toward the end of the shell, air will be sucked in through the port 17. At the same time any air between the outwardly moving piston 24 and the adjacent piston 19 will be compressed and will pass 15 through the passage 20, unseating the valve 22 therein so that this compressed air will get in advance of the piston 19. As the piston 19 is also moving at the same time, the air will be forced out through the outlet 14 20 into the manifold 15 and thence into the discharge pipe 16. On the return stroke the valves 22 and 28 will unseat so that air in advance of the pistons when moving in this direction will pass through the pistons and 25 be compressed between the pistons and pass through the outermost piston 19 into the adjacent end of the casing or shell. As this movement continues first in one direction and then in the other, it will be obvious that 30 air will be continuously drawn in, compressed between the pistons, and be forced out to wherever its use is needed.

From the foregoing description and a study of the drawings it will be apparent 35 that I have thus provided a comparatively simply constructed and easily operated air compressor which will rapidly compress air owing to the provision of the differential pistons having relative movement. It is 40 apparent that the quickness of the compression is dependent mostly upon the fact that double compression is obtained at both strokes.

While I have shown and described the preferred embodiment of my invention, it is of course to be understood that I reserve the right to make such changes in the form, construction, and arrangement of parts as will not depart from the spirit of the invention 50 or the scope of the subjoined claims.

Having thus described my invention, I claim:

1. A device of the character described comprising a cylindrical shell provided intermediate its ends with an air inlet opening and provided adjacent its ends with outlet

openings, a power driven reciprocatory piston rod within said shell, pistons secured upon said rod and provided with outwardly opening spring-pressed valves, a second piston rod within the shell, pistons on said second named rod and positioned appreciably closer together than said first named pistons, said second named pistons being provided with outwardly opening valves and being formed with openings through which said first named piston rod is slidable, racks formed on said piston rods, a transverse shaft, and pinions of different diameters meshing with the respective racks. 60 65 70

2. An air compressor comprising a shell provided intermediate its ends with an inlet opening and adjacent its ends with outlet openings, a power driven piston rod movable within said shell and reciprocating 75 therein, pistons on said rod having passages normally closed by outwardly opening valves, a second piston rod, pistons on said second named rod provided with passages normally closed by outwardly opening valves 80 and further provided with openings through which said first named piston rod is slidable, and means driven by said first named piston rod whereby to effect simultaneous movement of said second named piston rod and 85 second named pistons at a different speed with respect to the movement of the first named piston rod. 90

3. An air compressor comprising a shell provided intermediate its ends with an inlet opening and adjacent its ends with outlet openings, a power driven piston rod movable within said shell and reciprocating 95 therein, pistons on said rod having passages normally closed by outwardly opening valves, a second piston rod, pistons on said second named rod provided with passages normally closed by outwardly opening valves and further provided with openings through 100 which said first named piston rod is slidable, and means driven by said first named piston rod whereby to effect simultaneous movement of said second named piston rod and second named pistons at a different speed with respect to the movement of the first 105 named piston rod, said means comprising rack and pinion mechanism connecting and transmitting movement between said piston rods.

In testimony whereof I affix my signature.

EMORY LEE BLEVINS.
